UNITED STATES PATENT OFFICE.

EMIL WITZENMANN, OF PFORZHEIM, GERMANY.

PROCESS OF AND APPARATUS FOR MANUFACTURING LINED METALLIC HOSE.

No. 830,695.

Specification of Letters Patent.

Patented Sept. 11, 1906.

Application filed April 17, 1906. Serial No. 312,262.

To all whom it may concern:

Be it known that I, EMIL WITZENMANN, manufacturer, a subject of the Grand Duke of Baden, residing at 48 Holzgartenstrasse, 5 Pforzheim, German Empire, have invented new and useful Improvements in Processes of and Apparatus for Manufacturing Lined Metallic Hose, of which the following is a specification.

10 My invention relates to a process of and apparatus for manufacturing spiral metallic hose having an inner lining-hose of india-rubber or other suitable material.

15 The novel feature of the invention is that the lining-hose is fed through the hollow spindle of the metallic hose-making machine during the manufacture of the metallic hose in such manner that the finished hose complete with the lining can be drawn from the spindle. Prior to entering the hollow winding-spindle the lining-hose is pressed or folded together in the direction of its length, and after removal of the finished hose the lining-hose is again distended by conducting air, 25 liquid, or other suitable agent into it, so that the outer wall of the lining-hose lies tightly against the inner wall of the outer metallic hose.

20 One form of construction of a machine for carrying out the new process is illustrated in the accompanying drawings, in which—

Figure 1 is a side elevation of the machine; Fig. 2, a longitudinal section through the head of the winding-spindle with device for 35 pressing in the lining-hose. Figs. 3 and 4 are cross and longitudinal sections of a piece of metallic hose with collapsed lining. Figs. 5 and 6 are like views of the metallic hose after distension of the lining, Figs. 2 to 6 being 40 drawn to an enlarged scale.

The hose-winding machine is mounted on a suitable framing and furnished with a hollow spindle *a*, upon which the hose *b* is wound in well-known manner. The lining-hose of 45 rubber or other suitable material to be introduced into the metallic hose is wound on the reel *m*. At the opposite end of the machine is a reel *c*, to which the piece of finished metallic hose is connected. This reel *c* turns on 50 the pin *d* and is held by the frame *f*, which rotates on the axis *g g*, located at right angles to the pin *d*. Similarly the reel *m* turns on an axis located at right angles to the pin on 55 which it is mounted, the said axis, like the axis *g g*, forming a prolongation of the axis of

the spindle *a*. The rotation of the frame *f* is dependent upon the driving-gear for the spindle *a*, and thus also upon the rotation of the reel *m*.

In the constructional form illustrated 60 sprocket-gear *n* is shown transmitting the motion to sprocket-gear *i* by means of a spindle *h*, so that the frame *f*, the reel *c*, and the reel *m* rotate in the same direction as the spindle *a*. When a metallic hose is to be 65 provided with a rubber or other lining hose, the latter is fed from the reel *m* through the hollow winding-spindle to the reel *c*. In order to enable this to be done, the rubber hose *r* before entering the spindle *a* is pressed in or 70 folded together. For this purpose there may, for instance, be a roller *p* located in a recessed part of the head *o*, which roller presses in the hose unwinding from the reel *m*, Fig. 3, or the hose may be drawn from the 75 reel *m* in already-folded condition. After the lining-hose has been inflated it will lie tightly against the inner wall of the outer metallic hose and forms, as it were, an integral part of it. The metallic hose is wound 80 on the spindle *a* in well-known manner. Each time the spindle *a* has been wound the hose is automatically or by hand pushed off the spindle and with the lining wound onto the reel *c*.

85 The details of the apparatus may be varied in numerous ways. This applies in particular to the description of winding-machine employed. The essential feature of the invention is that the lining-hose is fed to the metallic hose during the course of manufacture of the latter and is pressed in or folded together in longitudinal direction prior to its entering the hollow winding-spindle.

Having thus described my invention, what 95 I claim as new, and desire to secure by Letters Patent, is—

1. The process of manufacturing lined spiral metallic hose, consisting in winding metallic hose on a hollow spindle, and simultaneously conducting a lining-hose through the spindle, and then removing the thus-lined metallic hose from the latter, substantially as described.

2. The process of manufacturing lined spiral metallic hose, consisting in winding metallic hose on a hollow spindle, and simultaneously conducting a lining-hose in collapsed condition through the spindle, removing the metallic hose with the lining-hose from the

latter, and then distending the lining-hose, by means of a suitable agent until it lies tightly against the inner wall of the metallic hose, substantially as described.

5. In apparatus for manufacturing lined spiral metallic hose, a hollow spindle, a lining-hose reel mounted at the head thereof and at right angles to the spindle-axis, and means for rotating the reel and spindle, substantially as described.

4. In apparatus for manufacturing lined spiral metallic hose, a hollow spindle a lining-hose reel mounted at the head thereof and at right angles to the spindle-axis, a

15 roller mounted between the reel and the spindle, for making a longitudinal fold in the lining-hose, on its entering the spindle, and

means for rotating the reel, spindle and roller, substantially as described.

5. In apparatus for manufacturing lined 20 spiral metallic hose, a hollow spindle, a lining-hose reel mounted at the head thereof and at right angles to the spindle-axis, a roller mounted in the spindle-head, for making a longitudinal fold in the lining-hose on 25 its entering the spindle, and means for rotating the reel and spindle, substantially as described.

In witness whereof I have hereunto signed my name this 2d day of April, 1906.

EMIL WITZENMANN.

In presence of—

Wm. HAHN,

ERNST ENTENMANN.
